UNITED STATES PATENT OFFICE.

GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ATTACHMENT-PLUG.

1,063,026.

Specification of Letters Patent. Patented May 27, 1913.

Application filed January 25, 1913. Serial No. 744,143.

To all whom it may concern:

Be it known that I, GILBERT W. GOODRIDGE, a citizen of the United States of America, and residing at Bridgeport, in the county of Fairfield and State of Connecticut, have invented a certain new and Improved Attachment-Plug, of which the following is a specification.

The present invention relates to attachment plugs and particularly to a device of the screw plug type, the object of my invention being to provide a screw plug of improved and efficient construction.

In the accompanying drawings, Figure 1 is a side elevation of an attachment plug embodying my invention in one form; Fig. 2 is a dropped elevation of the same, partly in section; Fig. 3 is an inverted plan of the plug, with the metal parts removed; Figs. 4 and 5 are vertical sections through the plug on the lines 4—4 and 5—5, Fig. 3 respectively and with the metal parts in position in Fig. 4; Fig. 6 is an inverted plan of the screw shell side contact; and Fig. 7 is a dropped perspective of the wire terminal for the shell drawn to an enlarged scale.

The present plug in the form shown comprises a one-piece body 10 of insulating material having an enlarged head portion 11 with peripheral flutings 12 to afford a firm grip. An external annular recess 13 is formed below the head of the plug to receive the spun-in upper edge of the screw-shell side contact 14. The lower edge of the screw-shell is spun over the shoulder 15 and is extended inward as a flange 16 overlying the base of the bay 17 formed in the entering end of the plug. A recess 18, formed in the base of the bay, receives the strap 19 the angled ends 20 of which project through apertures 21 in the flange 16 and form wings which confine the wire ends. A threaded perforation 22 in the strap registers with the perforation 23, in the flange 16, and receives the threaded shank of the binding screw 24 which enters the well 25 formed in the body of the plug.

The extreme of the entering end of the plug is recessed at 26 to receive the center contact plate 27. A portion of this plate overlies the axis of the plug and is perforated to receive the binding screw 28 which forms the center contact of the plug. A rivet 29 which passes through the plate 27 and the hole 30 in the end of the plug is

spread above the shoulder 31 and thus holds the plate in position.

The body of the plug is recessed at 32 in the outer end to receive the wires, while separate longitudinal passages 33 open from this chamber 32 to the respective wire terminals. A hollow rivet 34, which passes through the flange 16 at 35 aids in securing the screw shell in position and forms the lower portion of the passage 33 leading to 36 the shell terminal.

The present plug affords a device for which the one-piece porcelain body and its metal parts are easily and cheaply manufactured, readily assembled, quickly wired and efficient in use.

Various modifications in details of construction will readily suggest themselves.

I claim as my invention:

1. An attachment plug of the screw plug type comprising a one-piece body of insulating material having a lateral bay at its entering end, a screw shell side contact having a flange projecting inwardly into said bay, a center contact plate on the entering end of said plug, binding screws on said plate and flange respectively, said insulating body being provided with independent wire passages extending longitudinally through the plug body and opening adjacent said binding screws.

2. An attachment plug of the screw plug type comprising a one-piece body of insulating material having a head portion, a body portion and a portion of reduced size extending beyond the entering end of said body portion, a side contact mounted on said body portion and a center contact mounted on said portion of reduced size, said insulating body being provided with independent wire passages extending longitudinally through said insulating body, in combination with binding screws on the entering end of the plug for electrically connecting the wires to said center and side contacts.

3. An attachment plug of the screw plug type comprising a one-piece body of insulating material having a head portion, a body portion and a portion of reduced size extending beyond the entering end of said body portion, a side contact mounted on said body portion and a center contact mounted on said portion of reduced size, said insulating body being centrally re-

cessed in its head portion to form a wire receiving chamber and longitudinally recessed to form wire passages opening from said wire receiving chamber to the wire 5 terminal, in combination with binding screws on the entering end of the plug for electrically connecting the wires to said center and side contacts.

4. In an attachment plug of the screw 10 plug type comprising a one-piece body of insulating material having a lateral bay at its entering end, a screw shell side contact mounted on said body and having a flange projecting inwardly into said bay, a binding 15 screw passing through said flange and a wire passage through said insulating body and side contact flange opening adjacent said binding screw.

5. In an attachment plug of the screw 20 plug type comprising a one-piece body of insulating material having a lateral bay at its entering end, a screw shell side contact mounted on said body and having a flange projecting inwardly into said bay, a binding 25 screw passing through said flange and a hollow rivet securing said flange to the body and forming a wire passage opening adjacent said binding screw, substantially as described.

6. In an attachment plug of the screw 30 plug type, a one-piece body of insulating material, having on its entering end a center contact plate, a binding screw carried thereby axially of the plug and forming the 35 center contact of the latter, a solid rivet arranged longitudinally of the plug for securing said contact plate in position, said plug being provided with a longitudinal passage opening to the entering end of the 40 plug to one side of said rivet and center contact, to permit the passage of a leading-in wire to said center contact.

7. In an attachment plug of the screw 45 plug type, a one-piece body of insulating material, having on its entering end a center contact plate, a binding screw carried

thereby axially of the plug and forming the center contact of the latter, a shouldered passage through said plug body, a rivet passing through said center contact plate 50 and spread at one end above the shoulder in said passage, and a supplemental wire passage extending longitudinally of the plug and opening adjacent said binding screw.

8. In an attachment plug, a one-piece 55 body of insulating material, having a lateral bay at its entering end, the base of said bay being recessed, a screw shell side contact on said plug having a flange offset inwardly into said bay, a strap with threaded 60 perforation arranged in said recess and underlying said flange, together with a binding screw passing through said flange and threaded into said strap, for the purpose described. 65

9. In an attachment plug, a screw shell having a perforated securing flange, a strap with threaded perforation to receive a binding screw, said strap having angled lugs passing through said flange and forming 70 wire retaining lugs, substantially as described.

10. In an attachment plug of the screw 75 plug type, a one-piece insulating body having shoulders spaced longitudinally apart on the body of the plug and a lateral bay at the entering end of the plug, the base of said bay corresponding substantially with the level of one of said shoulders, in combination with a screw shell side contact 80 having its edges spun over said shoulders and being provided with a flange which in the assembled position of the parts overlies the base of said bay, substantially as described. 85

In testimony whereof I have signed my name to this specification, in the presence of two subscribing witnesses.

GILBERT W. GOODRIDGE.
